CLAIM

The ornamental design for a video conferencing apparatus, as shown and described.

DESCRIPTION

FIG. 1 is a perspective view showing the top and front sides of a video conferencing apparatus.

FIG. 2 is a front side elevation view of the video conferencing apparatus in FIG. 1.

FIG. 3 is a top plan view of the video conferencing apparatus in FIG. 1.

FIG. 4 is a bottom plan view of the video conferencing apparatus in FIG. 1.

FIG. 5 is a left side elevation view of the video conferencing apparatus in FIG. 1; and,

FIG. 6 is a right side elevation view of the video conferencing apparatus in FIG. 1.

The broken lines appearing in the Figures depict portions of the video conferencing apparatus that form no part of the claimed design.
